INDEX CARD AND HOLDER

Herman U. Doebler, New York, N. Y., assignor to
Remington Rand Inc., Buffalo, N. Y.

Application September 22, 1939, Serial No. 296,121

3 Claims. (Cl. 129—16.7)

This invention relates to an index card and holder particularly adapted for use in connection with visible indexes.

According to the invention a card holder or backing member has a front card detachably mounted thereon for cooperation to form a pocket that slidably receives an index card. The index card is adapted to receive suitable data that has been computed to give the answers to various calculations. Several different groups of calculated data for rating purposes may be placed on the record card in correlated order for display in connection with suitable indicator means such as openings, formed in the front card. The correlated data is arranged so that by sliding the record card back and forth in the pocket between the front card and the card holder, different portions of the index card will be displayed through the openings so as to display different data recorded on said card.

The invention comprehends the provision of an index card and holder wherein the holder is in the form of a backing sheet provided with guide means constructed to detachably receive the front card in cooperation therewith to form a pocket adapted to slidably receive a record card.

The invention more specifically provides a backing member in the form of a card holder provided with a pair of spaced parallel guides formed by securing folded transparent strips to the card holder in opposed relation with the opposite margins of the front card and the record card slidably engaged in the guideways between the folds of the pair of strips, while suitable means are provided on the front card and card holder for retaining the front card against sliding movement in the guideways. This means consists essentially of a wire stitch or the like securing the walls of the open end of the guide member on the free edge of the card holder together and to the card holder in a manner that one end of the card holder is closed. This prevents sliding movement of the front card in one direction, while sliding movement in the opposite direction is prevented by means of a projection on the card extending beyond the end of the other guide and arranged to engage the end of the guide.

In the drawing:

Fig. 1 is a plan view of a card holder with the front card and index card mounted thereon in accordance with the invention, the index card being shown in partially extended position in dot and dash lines.

Fig. 2 is a plan view of the card holder with

portions broken away and the index and front cards removed, for illustrating the manner in which the transparent guide members are attached to the card holder.

5 Fig. 3 is a cross section taken on line 3—3 of Fig. 1.

Fig. 4 is a cross section taken on line 4—4 of Fig. 1.

Fig. 5 shows the front card in perspective.

10 Card holder or backing sheet 1 is formed of a paper sheet provided with a row of openings 2 arranged in a line spaced inwardly a slight distance from one edge of the card holder to provide a hinge so that the major portion of card holder 1 may be swung on the hinge formed by openings 2 relative to margin 3. Margin 3 is secured by wire staples or the like to a supporting lug 4 in a manner well known in the art, the ends of lug 4 projecting beyond the ends of card holder 1 in order to engage with suitable supporting means, not shown, by which the card holder is mounted in connection with other similar card holders for support in a suitable tray or panel of a character that is well known.

20 The free margin of card holder 1 opposite to margin 3 has a folded transparent tip 5 engaged therover and secured thereto by means of wire stitches 6, 7 and 8. The corner of card holder 1 adjacent stitch 8 is cut out as indicated at 9 in Fig. 2 so that one end of stitch 8 extends through the front and rear fold portions of Celluloid tip 5 and secures these fold portions together to close the open end of the tip. The other end of stitch 8 engages in the adjacent portion of the sheet forming card holder 1 beyond the edge of tip 5 as shown in Fig. 2.

30 Wire stitches 6 and 7 as shown in Fig. 2 secure one fold of tip 5 to card holder 1 leaving the shorter fold overlying the front face of card holder 1 unattached to the card holder so as to provide an open pocket on the front face thereof. The edge of tip 5 overlying the front of the card holder is turned inwardly as indicated at 10 in Fig. 3. This type of tip construction is well known in the art.

40 Tip 5 forms a guide member on the free margin of card holder 1 and for the purpose of the present invention another tip 11 formed in the same manner as tip 5 is mounted adjacent the row of openings 2 forming the hinge. Tip 11 in opposed relation to tip 5, as illustrated, is arranged to extend toward the opening with the longer fold portion secured to card holder 1 by wire stitches 12. Tip 11 forms a guide parallel to tip 5, and as shown in Figs. 1 and 2, one end of tip 11 at

the right hand side of the card holder as illustrated, terminates short of the adjacent end of the card holder so that tip 11 is shorter than the card holder is wide.

A front record card 13 is slidably mounted in guides 5 and 11 shown in Fig. 1 and arranged in superimposed relation on top of card holder 1. The opposite margins of card 13 engage in the respective guides 5 and 11. The right-hand end of the card as shown in Fig. 1 engages wire stitch 8 thereby preventing endwise movement in one direction relative to card holder 1. Endwise movement of front card 13 in the opposite direction is prevented by projection 14 on the upper corner of card 13 extending beyond the end of tip 11 for engaging the end of the tip. The card is inserted and removed from tips 11 and 5 by flexing the card in the center to shorten the distance between the upper and lower edges to less than the distance between tips or guides 5 and 11. Upon insertion of the margins of card 13 in guides 5 and 11 in flexed condition the card is then released and allowed to flatten whereupon it assumes the position shown in Fig. 1.

A finger opening 15 is formed in the edges of front card 13 and card holder 1 on the left-hand end as shown in Fig. 1. Adjacent the end provided with finger opening 15, front card 13 is formed with a plurality of openings 16 arranged in aligned relation as shown in Figs. 1 and 5. These openings 16 form display openings for displaying data on index card 17 slidably mounted in the pocket formed between front card 13 and card holder 1. The opposite margins of index card 17 slidably engage in guides 5 and 11 in a manner that will be clear from an inspection of Fig. 1 of the drawing. Finger openings 15 allow the end of index card 17 to be manually grasped so that it may be slidably moved out of its housed position in the pocket between front card 13 and card holder 1. Slidable movement of index card 17 relative to front card 13 will cause any record matter printed thereon to be successively displayed through openings 16 in card 13.

This construction provides for the application of suitable tabulated data, data for computing insurance rates, or any other mathematical computation data or tables of various sorts to the face of card 17 by printing such data in lines across the card in alignment with apertures 16. The data in each line may be different so that various apertures 16 overlying different sections or lines of data on index cards 17 may display different correlated data through the different openings for each position of the card and in this way provide a convenient and speedy means of obtaining information of various sorts from index card 17. Card 17 may be slidably moved in and out from behind front card 13 in the operation of the device to obtain data on card 17 in properly arranged display through openings 16.

Card holder 1 with front card 13 and index card 17 may be conveniently arranged in a visible card index system of a character well known in the art to cooperate therewith in any desired manner to supply data for use in connection with such an index. Front card 13 may be used for any desired record information that it may be found desirable to enter thereon in connection with the index with which it is associated.

In this connection and in connection with index card 17 suitable indexing signals of various kinds may be utilized along the visible marginal edge of card holder 1 by engaging such signals,

as indicated at 18, in transparent tip 5. The margin of front card 13 engaged in tip 5 will be the visible margin of the card in a visible index system and may be designed to receive appropriate indexing information, and in addition, may be provided with suitable printed indications for cooperation with signal 18 such as the months of the year and the days of the month.

Front card 13 and index card 17 may be readily removed by flexing the same to disengage them from guides 5 and 11 and they may be replaced with new index cards using new data adapted for operation in connection with the keeping of any suitable record in card holder 1 that may be desired. Openings 16 may be arranged at any portion of index card 13 found desirable and in some cases their arrangement may not be in alignment as illustrated but may be staggered throughout different portions of the card.

The invention claimed is:

1. An index card and holder comprising a back supporting member of sheet material, a pair of spaced parallel guides mounted on said member, a front card having opposite margins engaged in said guides, means on said member and front card for retaining said card against sliding movement in said guides and in superimposed relation on said member to form a pocket therebetween, said front card being formed with a plurality of openings, and an index card slidable in said guides and in said pocket for the display of sections thereof through said openings.

2. In a card index, a back sheet member forming a card holder, a pair of folded strip members mounted on said card holder in spaced parallel and opposed relation to form guides, a front card having opposite margins slidable in said guides, means on the card holder and card for retaining said card in one position against sliding movement, said card being formed with a plurality of display openings, and an index card having opposite edges slidable in said guides and located between said front card and card holder and having portions showing through said display openings.

3. In a card index, a back sheet member forming a card holder, means on one margin for attachment to a support, said card holder having a hinge formed therein adjacent said means whereby the remainder of said card holder may be swung on said hinge relative to said margin, a folded transparent tip of sheet material embracing and mounted on the opposite margin of said card holder to form a guide, means securing the fold portions of said tip together at one end, another guide mounted on said card holder adjacent said hinge in parallel relation to said tip, a front card superimposed on said card holder with opposite margins slidably engaged in said guides for forming a pocket with said card holder, one end of said front card being adjacent said securing means for one end of said tip to retain said card against sliding movement in one direction, a projection on said card extending beyond the last-mentioned guide for engagement with the end thereof to retain said front card against sliding movement in the other direction, and a record card between said front card and card holder having opposite margins slidable in said guides for sliding movement relative to said front card and cooperation with indicating means on said front card for displaying correlated index data.

HERMAN U. DOEBLER.

CERTIFICATE OF CORRECTION.

Patent No. 2,254,889.

September 2, 1941.

HERMAN U. DOEBLER.

It is hereby certified that error appears in the printed specification of the above numbered patent requiring correction as follows: Page 2, second column, line 49, claim 3, for "hingle" read --hinge--; and that the said Letters Patent should be read with this correction therein that the same may conform to the record of the case in the Patent Office.

Signed and sealed this 28th day of October, A. D. 1941.
